Patented Feb. 11, 1919.

UNITED STATES PATENT OFFICE.

LYNN G. RILEY, OF WILKINSBURG, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,293,929.

Specification of Letters Patent. Patented Feb. 11, 1919.

Application filed April 23, 1915. Serial No. 23,415.

To all whom it may concern:

Be it known that I, LYNN G. RILEY, a citizen of the United States, and a resident of Wilkinsburg, in the county of Allegheny and State of Pennsylvania, have invented a new and useful Improvement in Systems of Control, of which the following is a specification.

My invention relates to systems of control, and it has special reference to the automatic series-parallel control of electric railway vehicle motors and the like.

One of the objects of my invention is to provide a relatively simple and reliable system of the above-indicated character for preventing undesirable rushes of current and too sudden acceleration of a vehicle during a predetermined portion of its accelerating period.

Another object of my invention is to provide a simple auxiliary means for use in connection with a "line relay" device for permitting the operation of certain switches to set up dynamic braking of vehicle motors upon an interruption of supply-circuit voltage.

Another object of my invention is to provide an improved type of bridging transition from series to parallel relation of the motors, whereby the acceleration during such transition may be effected more rapidly and smoothly than heretofore.

In the prior art, when employing the field-control type of system for electric vehicle motors, it has been customary to simultaneously exclude predetermined portions of the field windings of the respective motors from circuit, thereby causing undesirable rushes of current and too sudden acceleration of the vehicle. I provide automatic means for effecting the change from "full" to "normal" field strength of the respective motors successively, thus preventing the undesirable conditions referred to.

Moreover, when the supply-circuit voltage has temporarily failed so that the "line relay" switch has dropped to open the customary circuits, it has been impossible to actuate the motor-controlling switches to set up dynamic braking and retard the movement of the vehicle. My present system provides simple means to be actuated by the train operator to allow the action of such

switches in an emergency, whereby the vehicle speed may be controlled, as more fully set forth hereinafter.

In the accompanying drawing, Figure 1 is a diagrammatic view of the main circuits of a system of control embodying my invention; Fig. 2 is a diagrammatic view of the auxiliary governing circuits for the system shown in Fig. 1; Fig. 3 is a sequence chart of well known form for indicating the sequence of operation of the various switching devices that are illustrated in Fig. 1; and Fig. 4 is a complete diagrammatic view of one of the switching devices.

Referring to Fig. 1 of the drawing, the system here shown comprises a pair of suitable supply-circuit conductors respectively marked "Trolley" and "Ground"; a plurality of electric motors respectively having armatures A1 and A2 and subdivided field windings F1 and F2, to permit of field control of the motors; a reversing switch RS, preferably of the familiar electrically-controlled drum type, for simultaneously reversing the electrical relations of the respective armatures and field windings; a plurality of motor-controlling switches LS1, LS2, M2, JR, J, and G of a familiar electrically-controlled type; a mechanically-actuated switching apparatus PK, preferably of the drum type, that is employed in connection with a plurality of accelerating resistors R1 and R2 and also for varying the active amounts of the field windings during acceleration; and another accelerating resistor AR that is adapted to be short-circuited by the closure of the switches LS1 and LS2. The system is also provided with a limit switch L that is connected in circuit in a manner to be described, and an overload trip switch OT of a familiar type.

The apparatus PK is adapted to assume a plurality of operative positions 1 to 7, inclusive, and comprises a plurality of aligned control drums D1 and D2 that are respectively provided with operating shafts 1 and 2 upon which is mounted a centrally located pinion 3 that is adapted to mesh with a suitable rack member 4. A plurality of suitable pistons 5 and 6 are respectively secured to the ends of the rack member 4 and are disposed to operate within suitable cylinders 7 and 8, respectively. A suitable valve

member 9 is adapted, when actuated, to admit fluid-pressure from any suitable source (not shown) to the cylinder 7, and a second valve member 10 is normally adapted to admit fluid pressure to the cylinder 8. The valve members 9 and 10 are also adapted to be electrically controlled, through the agency of suitable coils 11 and 12, respectively, that are connected in the auxiliary system shown in Fig. 2, as hereinafter set forth.

The operation of the apparatus PK may be described as follows: In the position shown in the drawing, with both the magnet coils 11 and 12 deenergized, fluid pressure is admitted through the valve member 10 to the cylinder 8 to bias the piston 6 and the drums D1 and D2 to the position shown in the drawing, which corresponds to the off position of the master controller that is illustrated in Fig. 2. To effect movement of the drums D1 and D2 the magnet coils 11 and 12 are energized, whereupon fluid pressure is admitted through the valve member 9 to the cylinder 7 and is exhausted from the cylinder 8 through the valve member 10, thereby rotating the control drums through their successive operative positions. The general arrangement of parts, including the size of the valve openings and the customarily-provided drum star wheel device (not shown), is such that the apparatus PK is adapted to stop only in its definite positions, 1 to 7, inclusive, as will be understood. To arrest the movement of the drums in any position, it is merely necessary to deenergize the magnet coil 12, whereupon the valve opens to admit fluid pressure to the cylinder 8 and to balance the pressure in the cylinder 7, thereby maintaining the control drums D1 and D2 in the desired position until the magnet coil 12 is again energized. Where the magnet coil 12 is intermittently energized through the agency of the limit switch L in accordance with the value of the accelerating current, as set forth later, the control drums are given a step-by-step movement to gradually exclude from circuit the accelerating resistors R1 and R2 and to subsequently vary the active amounts of the field windings F1 and F2. To return the control drums D1 and D2 to the first position shown in the drawing, it is merely necessary to deenergize both magnet coils 11 and 12, whereupon fluid pressure is admitted to the cylinder 8 and is exhausted from the cylinder 7.

The limit switch L is provided with the customary series coil 13 that is here connected in series circuit with the armature A2 and is also provided with an auxiliary shunt-connected, differentially-wound coil 14 that is energized in the manner to be described in connection with the system shown in Fig. 2. The usual auxiliary contact members 15 for opening and closing circuits of

the auxiliary governing system are also associated with the limit switch.

The general operation of the system, so far as the main circuits of Fig. 1 are concerned and without regard to the particular auxiliary governing system that is illustrated in Fig. 2, may be set forth as follows. Energy is first supplied from the trolley conductor, through the switch LS1, the accelerating resistor AR, the armature A1, suitable contact members of the reversing switch RS, the "full" field winding F1, control fingers 16 and 17 that are bridged by contact segment 18 of the control drum D1, other contact members of the reversing switch RS, the accelerating resistor R1, the switch JR, the accelerating resistor R2, the armature A2, other contact members of the reversing switch RS, the "full" field winding F2, control fingers 19 and 20 that are bridged by contact segment 21 of the control drum D2, again through the reversing switch RS and the actuating coils 13 of the limit switch L to the negative conductor.

As indicated by the sequence chart of Fig. 3, the switch LS2 is next closed to short-circuit the accelerating resistor AR and the apparatus PK is then gradually moved, in the step-by-step manner hereinbefore described, to gradually short-circuit the resistors R1 and R2: In position 2 of the control drums, a contact segment 22 engages control fingers 23 and 24 to short-circuit one section of the resistor R1; in position 3, a contact segment 25 bridges control fingers 26 and 27 to exclude a portion of the resistor R2 from circuit; in position 4, control finger 28 engages contact segment 29 of the control drum D1 to complete the short-circuit of the resistor R1; while, in position 5, a control finger 30 engages contact segment 25 of the drum D2 to complete the exclusion from circuit of the resistor R2.

The transition of the motors from series to parallel relation is then effected by the initial closure of the switch J, the subsequent opening of the switch JR and the concurrent return of the drums D1 and D2 to their initial position 1, and the final closure of the switches M2 and G accompanied by the opening of the switch J, as hereinafter set forth in detail, in connection with Fig. 2. The apparatus PK is then actuated through its first five positions, in a manner similar to that already described.

When drums D1 and D2 are actuated to position 6, control finger 32 engages contact segment 33 and control finger 16 is disengaged from contact segment 18, whereby a predetermined portion of the field winding F1 is excluded from circuit to produce further acceleration of the corresponding motor, in accordance with familiar practice. As soon as the control drums D1 and D2 occupy their final position 7, a control finger

34 engages contact segment 35 of the drum D2, while control finger 19 breaks contact with the contact segment 21 thereof, thereby reducing the "full" field winding to "normal" field winding connection in the other motor, in the same manner as that described in connection with the field winding F1.

It will be observed that the resistors R1 and R2 are gradually excluded from circuit 10 in corresponding successive steps and that the active amounts of the field windings F1 and F2 are also varied successively and controllably in accordance with the value of the accelerating current, thereby preventing 15 an undesirable rush of current and providing a relatively smooth acceleration during this portion of the motor operation.

Reference may now be had to Fig. 2 which illustrates the actuating coils of the various 20 motor-control switches that are shown in Fig. 1; a plurality of electrical interlocking members of a familiar type that are associated with, and adapted to be actuated by, the particular switch in accordance with the 25 legends employed, as more fully illustrated in Fig. 4; a master controller MC and a master reverser MR for supplying energy to the various actuating coils from a suitable source of energy, such as a battery B; a 30 plurality of train-line conductors TL and a "line relay" switch LR of a familiar type.

The master controller MC is adapted to assume a plurality of operative positions, *a*, *b*, and *c*, respectively corresponding to initial-series, full-series, and full-parallel relation of the motors. However, the system shown being automatic, the controller may be directly thrown to its final position *c*, as will be understood. The master reverser MR 40 is adapted to assume the customary "forward," "off" and "reverse" positions, and is provided with suitable corresponding contact members, as hereinafter described.

The line relay switch LR is shown as provided 45 with an actuating coil 36, the respective ends of which are adapted to be connected to the supply circuit conductors "Trolley" and "Ground," as indicated in Fig. 2. The switch is adapted to occupy a lower position, when the coil 36 is deenergized, for completing certain auxiliary circuits, and an upper position when the coil 36 is energized to complete other auxiliary circuits, as hereinafter more fully set forth.

The shunt coil 14 of the limit switch L 55 is shown as energized from the battery B through the master controllers and a contact segment 37 of the drum D2, and its energizing effect upon the limit switch opposes the action of the series coil 13 and may be varied in accordance with predetermined conditions by means of a suitable variable resistor 38. The particular means for varying the resistor 38 of this control device, however, forms no essential part of my

present invention and is fully shown and described in a co-pending application of Francis H. Shepard, Serial No. 785, filed January 6, 1915, and assigned to the Westinghouse Electric and Mfg. Company.

Assuming the master reverser MR to be moved to its "forward" position and the master controller MC to be actuated to its final running position *c*, the automatic operation of the auxiliary control system may be 70 described as follows: A circuit is first established from one terminal of the battery B through conductor 40, train-line conductor 41, conductor 42, control fingers 43 and 44 that are bridged by contact segment 45 of the master reverser MR in its "forward" 75 position, conductor 46, control fingers 47 and 48 that are bridged by contact segment 49 of the master controller in its positions *a*, *b* and *c*, conductors 50 and 51, coöperating 80 contact members 51^a of the overload trip OT, conductor 52, electrical interlock 53 J—out, conductor 54, interlock M2—out, the actuating coil of the switch JR, conductors 55 and 56, train-line conductor 57, conductor 58, control fingers 59 and 60 that are bridged by contact segment 61 in the forward position of the master reverser MR, and thence to the negative conductor.

Another circuit is simultaneously established from train-line conductor 41, through conductor 62, contact segment 63 of the reversing switch RS, conductor 64, coöperating contact members 64^a of the overload trip OT in its closed position, contact segment 65—drum—1 that is adapted to complete the circuit in question when the apparatus PK occupies its initial position 1, conductor 65^a, actuating coil of the switch LS1, conductor 66, coöperating stationary and 90 movable contact members 67 of the "line relay" switch LR in its upper position, and thence through conductor 56 to the negative conductor in the manner already described. As soon as the switch LS1 has closed, an 100 interlock LS1—in bridges the contact segment 65—drum—1, thereby insuring the closure of the switch LS1 throughout the subsequent operation of the system, irrespective of the position of the control drums D1 115 and D2.

Another circuit is then established from conductor 65^a through conductor 68, interlock J—out and the magnet coil 11 of the apparatus PK to the negative conductor 120 through conductor 66 and the "line relay" switch contact members 67, as hereinbefore mentioned. A further circuit is established from energized contact segment 69 of the master controller MC in its positions *b* and *c*, through control fingers 69^a, conductors 70, train-line conductor 70^a, conductors 71 and 72, contact segment 37 of the control drum D2 in any of its first four positions, conductors 73 and 74, interlock 75—JR—in, 130

conductor 76, coöperating contact members 15 of the limit switch L, provided the limit switch has dropped to its lower position, conductor 77, interlock 78—LS2—out, the 5 actuating coil of the switch LS2, interlock LS1—in and the negative-connected conductor 55. As soon as the switch LS2 has closed to short-circuit the accelerating resistor AR, the energizing circuit for its actuating coil is transferred through interlock 78 and conductor 78^a to the conductor 68.

The closure of the switch LS2 causes the establishment of another control circuit from conductor 77, as soon as the limit switch L has again dropped to its lower position, through interlock 79—LS2—in, conductor 80, interlock J—out, and the magnet coil 12 of the apparatus PK to the negative-connected conductor 66.

20 The two magnet coils 11 and 12 of the apparatus PK being thus energized, the control drums D1 and D2 will move forward in a step-by-step manner, in accordance with the position of the limit switch L, to gradually effect the short-circuiting of the resistors R1 and R2, as hereinbefore described.

After the drums leave position 4, the contact segment 37 of drum D2 breaks the connection between conductors 72 and 73, thus 30 deenergizing the magnet coil 12 of the drums, irrespective of the position of the limit switch L. In this way, the drums are prevented from passing beyond position 5 while the interlock 75 of the switch JR occupies its "in" position, or, in other words, 35 while the motors are connected in series relation.

As soon as the apparatus PK has reached its final resistor-short-circuiting position 5, 40 another circuit is established from an energizing contact segment 81 in position c of the master controller through control finger 82, conductors 83 and 83^a, contact segment 84 of the control drum D1 in any of its 45 positions 5 to 7, inclusive, conductor 85, interlock G—out to the actuating coil of the switch J and the negative-connected conductor 55.

As soon as the switch J is closed, the 50 switch JR is opened by reason of the exclusion from its control circuit of the interlock 53—J—out, and the magnet coil 11 of the apparatus PK is simultaneously deenergized by reason of the exclusion from its 55 control circuit of the corresponding interlock J—out. The magnet coil 12 being deenergized, as already pointed out, the control drums D1 and D2 are returned to their initial position 1 by reason of the concurrent 60 deenergization of the magnet coils 11 and 12, as hereinbefore explained.

Provided the limit switch L occupies its lower position, a circuit is next established from conductor 77, through interlock 65 79—LS2—in, conductor 86, interlock 87

drum 1, interlock 87^a—M2—out, conductor 87^b, interlock JR—out, the parallel-connected actuating coils of the switches M2 and G, and conductor 55 to the negative conductor. The closure of the switch M2 closes a holding circuit therefor from conductor 87^b, through interlock 87^a and conductor 87^c to the conductor 52.

Whereas, in the usual type of "bridging" series-parallel control, the J switch is closed 75 in accordance with the position of a limit switch after the various accelerating resistors have been completely short-circuited, and the initial short-circuits of the resistors are thereafter removed to render them adaptable for subsequent service in connection with the parallel operation of the motors, and the switches M2 and G are finally brought in to complete the initial parallel connection of the motors, it will be observed 80 that, in the bridging transition just described, the J switch is closed to substitute for the initial short-circuits of both resistors R1 and R2, irrespective of the limit switch L, as soon as the accelerating resistors have 85 been initially completely short-circuited, and the control drums D1 and D2 are returned to their initial position 1 to remove the initial short-circuits from the resistors R1 and R2, while the limit switch L is being 90 held in its upper position by the flow of current incident to the final short-circuit of the accelerating resistors. Consequently, as soon as the limit switch drops to its lower position, the switches M2 and G can be immediately closed in the manner just recited to directly dispose the motors in initial parallel relation, and the transition of the motors from series to parallel relation is accomplished more rapidly than heretofore 95 100 and with a more continuous and uniform load upon the motors, thereby providing a smooth and more satisfactory operation of the motors during the transition period.

As soon as the switch J has been opened, 110 by reason of the exclusion from its control circuit of the interlock G—out upon the closure of the switch G, and provided the limit switch L occupies its lower position, the energizing circuit of the actuating coil 11 of the apparatus PK is completed in a manner similar to that hereinbefore described, and the magnet coil 12 is energized through the conductors 71 and 71^a, interlock 75—JR—out, the conductor 76, etc., as already set forth, whereupon the apparatus moves forward through its successive positions in the step-by-step manner set forth below, to gradually short-circuit the accelerating resistors R1 and R2, until the position 5 is reached.

The action of the drums D1 and D2 is somewhat different during parallel motor operation from the action during series operation, by reason of the fact that the series 130

actuating coil 13 of the limit switch L is adapted to receive the current from the armature A2 only. During series operation, the same current traverses both armatures, 5 so that the limit switch lifts to temporarily arrest the movement of the drums whenever a section of either the resistor R1 or the resistor R2 is short-circuited. The drums move forward, therefore, one step at a time. 10 On the other hand, during parallel motor operation, the limit switch lifts only when the current traversing the armature A2 exceeds a predetermined value. The drums thus move forward two steps between stops, 15 as indicated in the sequence chart, inasmuch as the current traversing the armature A1 does not influence the limit-switch coil. However, the movement of the drum between stops is not too rapid to permit the 20 active amounts of the field windings F1 and F2 to be varied successively in drum positions 6 and 7 to thus partially reduce the rush of current, as described in connection with Fig. 1.

25 In order to further reduce the accelerating current during field-changing conditions, the shunt-connected coil 14 of the limit switch L is rendered inoperative by reason of the contact segment 37 of the drum D2 30 again breaking the connection between conductors 72 and 73 after the drums leave position 4. In this case, however, the magnet coil 12 of the drums is not deenergized, by reason of the interlock 75 of the switch JR 35 occupying its "in" position, as already mentioned.

Since the actuating coils 13 and 14 of the limit switch L are adapted, when energized, to oppositely or differentially influence the 40 switch, it follows that, with the coil 14 excluded from circuit, the effect of the series coil 13 will be strengthened, or, in other words, the limit switch will lift at a relatively low value of accelerating current after 45 the drums D1 and D2 occupy position 5, thereby further preventing undesirable current peaks during field-changing conditions.

When the control drums D1 and D2 occupy their final operating position 7, the 50 two motors are disposed in full parallel relation with "normal" field strength in each motor.

The emergency operation of the "line relay" switch LR will now be described: If 55 the supply-circuit voltage fails, or if, for any other reason, the switch LR drops to its lower position, the energizing circuits of the various actuating coils that are connected to the conductor 66 are broken at 60 the switch by reason of the interruption of the connection between conductors 66 and 56. If it is desired to operate certain of the motor-controlling switches to effect dynamic braking of the motors under emergency conditions, an auxiliary switching device or

push-button PB, that is preferably located near the master controller, may be actuated by the train operator, whereupon a circuit may be completed from the actuating coils of the switches to be actuated through conductor 66, the coöperating contact members 67 of the "line relay" switch LR in its new or lower position, conductor 88, train-line conductor 88^a, conductor 89, the push-button PB in its operative position, conductor 90, 70 control fingers 91 and 60 that are bridged by the contact segment 61 in the forward position of the master reverser, and thence to the negative conductor. Upon the concurrent operation of the push-button PB and the master controller MC, therefore, the actuating coils of the various motor-controlling switches, that are connected to the conductors 66, may be energized and the switches may be operated to set up dynamic 80 braking through the closed motor circuit, with the "line relay" switch occupying its lower or emergency position, as will be understood.

I do not wish to be restricted to the specific circuit connections or arrangement of parts herein set forth, as various modifications of my invention may be made without departing from the spirit and scope thereof. I desire, therefore, that only such limitations shall be imposed as are indicated in the appended claims. 95

I claim as my invention:

1. In a system of control, the combination with a plurality of electric motors severally having armatures and field magnet windings, of means for connecting said motors in various circuit relations, a plurality of accelerating resistors, a control drum comprising contact means for gradually excluding said resistors from circuit and other contact means for successively varying the active portions of the field winding to effect acceleration of the motors, when the latter are connected in various circuit relations, 100 and means actuated in accordance with the accelerating current for automatically operating said drum from its initial to its final position in a step-by-step manner. 105

2. In a system of control, the combination with a plurality of electric motors severally having armatures and subdivided field-magnet windings, of means for connecting said motors in series and in parallel relation, a plurality of accelerating resistors, 120 a multi-position control drum, and automatic means governed by the current flowing through the motors for operating said control drum in a forward direction to gradually exclude the resistors from circuit 125 when the motors are in series relation, for returning the control drum to initial position and for operating the drum again in a forward direction to successively exclude portions of said resistors and portions of 130

3
said field windings from circuit when the motors are connected in parallel relation.

5 3. In a system of control, the combination with an electric motor, and a plurality of controlling devices therefor, of a switching device adapted, under normal conditions, to permit the actuation of a predetermined number of said controlling devices, and adapted, under predetermined conditions, to 10 prevent the actuation of certain controlling devices, and auxiliary means for rendering said switching device again fully operative under other predetermined conditions.

15 4. In a system of control, the combination with a supply circuit, an electric motor, and a plurality of controlling devices therefor severally provided with actuating coils, of a switching device adapted, in its normal position, to permit energization of certain 20 actuating coils and adapted to assume a new position to prevent the energization of said certain coils upon an interruption of the supply-circuit voltage, and auxiliary manually-operable means adapted to thereupon 25 permit a reenergization of said certain coils.

30 5. In a system of control, the combination with a supply circuit, an electric motor, and a plurality of controlling devices therefor severally provided with actuating coils, of an auxiliary source of energy, a relay device adapted, while energized from said supply circuit, to complete an energizing circuit from said auxiliary source for certain actuating coils and adapted to assume a new 35 position to open the energizing circuit of said certain actuating coils upon an interruption of the supply-circuit voltage, and auxiliary manually-operable switching means for re-completing said last energizing circuits through the new position of said relay device.

40 6. In an automatic series-parallel system of control, the combination with a plurality of electric motors and a plurality of accelerating resistors, of means for gradually excluding said resistors from circuit to effect acceleration of said motors to full series relation, a switching device adapted to be thereupon substituted for said resistor-excluding means to adapt the resistors for 45 subsequent service, means dependent upon predetermined conditions for thereupon directly disposing the motors in parallel relation, with said resistors in the respective motor circuits, and means for again effecting the exclusion from circuit of said resistors to accelerate the motors to full 50 parallel relation.

55 7. In an automatic series-parallel system of control, the combination with a plurality of electric motors and a plurality of accelerating resistors, of a control drum adapted to be moved through successive positions in accordance with the accelerat-

65 ing current to exclude said resistors from circuit to effect acceleration of said motors to full series relation, a switching device adapted to be thereupon substituted for said resistor-excluding drum, means for then returning said drum to its original position 70 to adapt said resistors for subsequent service, a plurality of switches dependent upon the accelerating current for thereupon directly disposing the motors in parallel relation, with said resistors in the respective 75 motor circuits, and means for then again effecting the operation of said drum to accelerate the motors to full parallel relation.

80 8. In a system of control, the combination with an electric motor, of a multi-position controlling device adapted to effect motor acceleration, a switching device provided with a plurality of actuating coils and adapted, under predetermined conditions, to govern the operation of said controlling device, and means dependent upon the position of the controlling device for rendering one of said coils operative or inoperative.

85 9. In a system of control, the combination with an electric motor, of a multi-position controller adapted to effect motor acceleration, a limit switch provided with a plurality of actuating coils energized from different sources and adapted to govern said controller in accordance with accelerating 95 current conditions, and contact means dependent upon the position of the controller for rendering one of said coils operative or inoperative.

100 10. In a system of control, the combination with an electric motor, of a multi-position controller adapted to effect motor acceleration, a limit switch provided with a plurality of differentially-energized actuating coils and adapted to govern said controller in accordance with accelerating current conditions, and contact means for rendering one of said coils inoperative in certain controller positions to thereby cause 105 said limit switch to operate at a relatively 110 low current value.

115 11. In a system of control, the combination with an electric motor having an armature and a sub-divided field magnet winding, of an accelerating resistor, a multi-position controller adapted to gradually short-circuit said resistor and to subsequently vary the active amount of said field winding, an auxiliary source of energy, a limit switch provided with a plurality of 120 differentially-disposed actuating coils respectively energized from the motor current and said auxiliary source and adapted to govern the operation of said controller in accordance with accelerating current conditions, and contact means for rendering the auxiliary-source energized coil inoperative when said resistor is short-circuited,

whereby the motor current during field-changing conditions is maintained at a relatively low average value.

12. In a series-parallel system of control, 5 the combination with a supply circuit, and a plurality of electric motors severally having armatures and subdivided field-magnet windings, of a plurality of accelerating resistors, a multi-position accelerating controller, a plurality of actuating coils therefor, an auxiliary source of energy, a limit switch provided with a pair of differentially-disposed actuating coils respectively energized from the motor current and said 10 auxiliary source and adapted to govern the operation of said controller in accordance with accelerating current conditions, means for initially energizing the controller-actuating coils to effect the gradual short-circuit of said resistors with the motors in series relation, means including contact means on said controller for effecting the return of the controller to its initial position during transition of the motors to parallel relation, 15 means for again effecting the short-circuit of said resistors, and means for then employing said contact means to render the auxiliary- 20 source-energized coil of the limit switch inoperative and means for thereupon permitting said controller to successively exclude 30 predetermined portions of the field windings from circuit, whereby the motor current during field-changing conditions is maintained at a relatively low average value. 25
13. In a system of control, the combination with a supply circuit, a plurality of motors having armature and field windings, a plurality of resistors in the circuit of said motors and a drum controller, of means for connecting said motors in series and in parallel relation across the supply circuit, and means governed by the current flowing through the motors for effecting a continuous automatic action, including operating said controller to gradually exclude said 40 resistors from circuit when the motors are in series relation, effecting transition of the motors, and excluding said resistors and a portion of said field windings when the motors are in parallel relation. 45

In testimony whereof, I have hereunto subscribed my name this 19th day of April 1915.

LYNN G. RILEY.
